(57) **CLAIM**

The ornamental design for a pizza saver bag, as shown and described.

DESCRIPTION

FIG. 1 is a perspective view of a first embodiment of a pizza saver bag showing my new design;

FIG. 2 is a top elevational view, the bottoms elevational view being a mirror image thereof;

FIG. 3 is a right side elevational view, the left side being a mirror image thereof;

FIG. 4 is a front elevational view thereof;

FIG. 5 is a rear elevational view thereof;

FIG. 6 is a perspective view of a second embodiment of a pizza saver bag showing my new design;

FIG. 7 is a top elevational view, the bottoms elevational view being a mirror image thereof;

FIG. 8 is a right side elevational view, the left side being a mirror image thereof;

FIG. 9 is a front elevational view thereof; and,

FIG. 10 is a rear elevational view thereof.

The broken lines showing the mechanical sliding fastener device in FIGS. 1-10 are for illustrative purposes only and form no part of the claimed design.
